UNITED STATES PATENT OFFICE.

PAUL BONCI, OF POCATELLO, IDAHO.

CARBURETOR DEVICE.

Application filed January 13, 1926. Serial No. 80,899.

This invention relates to improvements for hydrocarbon engines, having more particular reference to a novel provision of an improved device for increasing the power of the engine. Another object is to provide a device for preventing and removing carbon deposits within the cylinders. A further object is to provide a device which is automatically operated.

For further comprehension of the invention, and of the objects and advantages thereof, reference will be had to the following description and accompanying drawing, and to the appended claim in which the various novel features of the invention are more particularly set forth.

Fig. 1 of the drawing shows my improved device as it would appear when attached to an engine.

Fig. 2 is an enlarged central longitudinal sectional view of the automatic needle valve used in combination with my device.

Fig. 3 is an enlarged fragmentary side elevational detail view of my improved device.

Fig. 4 is an enlarged central longitudinal sectional view of the Venturi tube used in connection with my improved device.

Referring to the accompanying drawing, it will be seen that the hydrocarbon engine 10 of ordinary construction and design is provided with an exhaust manifold 11, and an intake manifold 12 which communicates with the carburetor 13 and the fuel intake member 14.

From the foregoing description it will be seen that the common engine is used in combination with my improved device.

My improved device consists in general of a container 15 attached to any convenient place on the engine 10, such as designated by the numeral 16 on the accompanying drawing. The lower extremity of the tube 17 is connected with the casing 20 from which the tube 17 is connected to the inlet manifold 12 as designated by the numeral 18 on the accompanying drawing. Adjacent to the lower extremity of the tube 17 is provided a shut off valve 19 of ordinary construction, such as commonly used for this purpose. The tube 17 is also provided with an automatic valve casing 20 in which the valve 21 is slidably mounted. The valve 21 is provided with a stem 22, an enlarged head 23 with its periphery being a slidable fit in the casing 20, and a guide 24 having an

aperture to accommodate slidably the valve stem 22, and a spring 25 superimposed between the enlarged head 23 and the guide 24. The foregoing construction being such as will normally hold the valve 21 against the seat 26 formed in the casing 20.

The Venturi tube 27 is a slidable fit in the tube 17, and is held in place by means of a set screw 28, or any similar suitable threaded member. The adjustable air inlet comprises an elongated slot 29 conveniently located in the tube 17, and a tubular member 30, a slidable fit on the tube 17, and having an elongated slot 31 and a set screw located therein threadedly attached to the tube 17, as a means of securing any desired opening of the said elongated slot 29.

It will be understood that the relative positions of the various members comprising my improved device is clearly shown in Figure 1 of the accompanying drawing, and that said various members are suitably connected to the said tube, which is cut and threaded as may be required.

Referring to the operation of my improved device, the container 15 is filled with castor oil and the shut off valve is opened. When the engine is running, by means of the suction in the intake manifold 12 and in the tube 17, the valve stem 22 will be sucked or drawn from its seat 26, allowing a certain amount of the castor oil in the container 15 to be sucked into the intake manifold 12 where it will be mixed with the vapor from the carburetor 13, and then sucked through the intake valves, not shown on the accompanying drawing, and then into the cylinders of the engine 10.

It is obvious that by opening the elongated aperture 29 that air may also be admitted to the manifold 12. In order to "speed up" or increase the velocity of the mixture, castor oil and air, I have provided the Venturi tube 27, it being understood that the last mentioned element is of ordinary design, and that same may be replaced by various different sizes of Venturi tube as may be desirable to engines of different characteristics.

It will be further understood that my improved device may be made of any suitable materials such as commonly used in devices of this nature.

While I have above described the preferred form, construction and arrangement of the several elements employed, it will be understood that the device is nevertheless,

susceptible of considerable modification therein, and I therefore reserve the privilege of resorting to all such changes as may be fairly embodied within the spirit and scope 5 of the invention as claimed.

Having thus described my invention, what I claim as new, and desire to protect by Letters Patent of the United States is as follows:—

- 10 Mechanism for supplying oil to an internal combustion engine comprising an oil reservoir, a tube for conveying oil from said reservoir to the manifold of said engine, a Venturi tube removably mounted in said 15 supply tube adapted to be removed for re-

placement thereof, the tube for conveying oil from the reservoir to the manifold being provided with an air inlet, a tubular member slidably mounted on the last mentioned tube, and means for adjustably fastening the 20 tubular member for regulating the mixture of air with the oil from said reservoir, and an automatic valve disposed in said latter mentioned tube for controlling the flow of oil from said reservoir, said valve being adapted 25 to be opened by the suction of said engine.

In testimony whereof I have affixed my signature.

PAUL BONCI.
